UNITED STATES PATENT OFFICE.

HERBERT AUSTIN, OF BROMSGROVE, ENGLAND.

TIME-FUSE FOR EXPLOSIVE SHELLS OR BOMBS.

1,342,413.

Specification of Letters Patent.

Patented June 8, 1920.

Application filed June 26, 1917. Serial No. 176,985.

To all whom it may concern:

Be it known that I, HERBERT AUSTIN, a subject of the King of Great Britain, and residing at Bromsgrove, in the county of Worcester, England, engineer, have invented certain new and useful Improvements in Time-Fuses for Explosive Shells or Bombs, of which the following is a specification.

In priming (that is to say, charging with time fuse material) a time fuse for a shell or bomb, it has been found in practice advisable to use a lead or other soft metal or composition tube charged with such material and to lay this tube within a groove which is provided therefor. It has been found, however, that it cannot be relied upon that the detonation will, in all cases, fire the fuse material within the tube unless the tube has been previously punctured.

Now, this invention comprises, as to its main feature, a cutter which is operated by the explosive force of the detonation and cuts the tube; and to insure that the material within the tube will with certainty be exposed to the flame of the explosion, an opening is formed down the cutter which will be partially carried, by the force of the explosion, into the fuse material, this opening being in communication with the detonator and thus insuring that the fuse material will be directly exposed to the flame of the explosion.

In order that the invention may be clearly understood, I will now describe practical applications of the same which are illustrated, by way of example, by the drawings herewith, of which:

Figure 1 is a section of a fuse to which the invention is applied, the section being taken lengthwise of the axis of the fuse.

Fig. 2 is a side elevation of the fuse shown by Fig. 1.

Fig. 3 is a section taken in the plane indicated by line 1—1 of Fig. 1.

Fig. 4 is a considerably enlarged view of the portion of Fig. 1 which shows the means by which the cutting of the tube is effected.

Fig. 4^a is a detached view of the cutter as seen looking in the direction of the arrow Fig. 4.

Fig. 5 is a corresponding view of Fig. 4 showing a modification of the means by which the cutting of the tube is effected.

Fig. 5^a is a detached view of the combined cutter and striker needle shown by Fig. 5 as seen looking in the direction of the arrow of such figure.

Referring first to Figs. 1 to 4^a inclusive, A is the base of the fuse within a groove a a' of which is inserted a tube n which contains time fuse material. B is the dome, which may be turned in relation to the base, and C a central pin which is screwed into the base and passes through the crown of the dome and is formed with a head c between which and the dome is interposed a spring washer E. A lug D¹ is formed in from one side of the dome B, and slidably fitted within an opening d of the lug is a cutter m. The base m' of this cutter is round and has a sliding fit within the opening d, and the cutting edge is directed rearward. Within the opening d, and forward of the cutter, is located a detonator d', and within a portion of reduced diameter of the said opening which is forward of the detonator is slidably fitted a striker needle h³. H is a circular hammer which is normally held forward within the dome B by a spiral spring J which surrounds the pin C. When the shell or bomb to which the fuse has been applied is shot forward, the hammer H hangs back, owing to its inertia, and strikes the striker needle h³ and drives its point into the detonator d', and the force of the detonation drives the cutter forward into the fuse tube n.

A hole m² is drilled through the center of the base m' of the cutter and for such distance into the blade m as provides an opening m³ in the blade which will insure that when the cutter has been driven into the tube n such opening will be exposed to the fuse material within the tube, whereby such fuse material will be exposed to the flame of the detonation which passes through the base. A shearing pin g is passed through the side of the dome B and into the side of the base m' of the cutter, the purpose of this pin being that the cutter, and consequently the detonator, may be depended upon to offer sufficient resistance to the force of the striker needle to insure that the needle will fire the detonator, the force of the detonation then causing the base of the cutter to shear the pin.

The striker needle h^3 is formed with a collar h^4 which has a sliding fit within the portion of reduced diameter of the opening d , and this collar is normally against a shoulder of such opening, and a head h^5 of such needle projects through a portion of still further reduced diameter of such opening, and the hammer H strikes against the head to drive back the needle into the detonator d' .

Referring now to Figs. 5 and 5^a, the striker needle h^3 is in this case formed with the cutter and projects from the middle of the base thereof at the opposite side to that from which the cutter blade m projects. The detonator d' is in position immediately forward of the needle h^3 , and beyond the detonator is a pin p which is formed with a collar p' which bears against the forward face of the detonator, and with a shank which is fitted slidably through a hole of reduced diameter which is formed through the forward end of the lug D^1 . The hammer H , as it strikes back in relation to the shell or bomb, strikes against the pin p and drives the detonator d' against the striker needle h^3 , and the force of the detonation drives the cutter into the fuse tube. In this case two holes m^2 are drilled through the base m' of the cutter, inclining toward and joining one another and running a sufficient distance into the cutter blade m to insure that an opening m^3 will be formed through the blade which will enter and be exposed to the fuse material when the cutter has been driven into the fuse tube n . In this case, also, a shearing pin q is shown to pass through the side of the dome B and to enter the base m' of the cutter, the purpose in this case being to support the needle and insure that it will fire the detonator.

Having fully described my invention, what I claim and desire to secure by Letters Patent, is:—

1. A time fuse for an explosive shell or bomb, having a groove, a tube containing time fuse material located within such groove, a detonator, a cutter which is exposed to the force of the detonation, a striker needle, and a hammer which, owing to its inertia, moves back in relation to the fuse, as the shell or bomb is shot forward, and thereby brings the striker needle and the detonator into contact with one another, causing detonation which drives the cutter into the tube, substantially as set forth.

2. A time fuse for an explosive shell or bomb, having a groove, a tube containing time fuse material located within such groove, a detonator located within a chamber of the fuse, a cutter within such chamber, a striker needle, and a hammer which, owing to its inertia, moves back in relation to the fuse, as the shell or bomb is shot forward, and brings the striker needle and the

detonator into contact with one another, causing detonation which drives the cutter into the tube, substantially as set forth.

3. A time fuse for an explosive shell or bomb, having a groove, a tube containing time fuse material located within such groove, a detonator, a cutter which is exposed to the force of the detonation, a striker needle, and a hammer which, owing to its inertia, moves back in relation to the fuse, as the shell or bomb is shot forward, and thereby brings the striker needle and the detonator into contact with one another, causing detonation which drives the cutter into the tube, and said cutter formed with an opening which at one end is exposed to the flame of the detonation and at the other end is exposed, when the cutter has entered the fuse tube, to the fuse material within the tube, substantially as set forth.

4. A time fuse for an explosive shell or bomb, having a groove, a tube containing time fuse material located within such groove, a detonator, a cutter which is exposed to the force of the detonation, a striker needle, and a hammer which, owing to its inertia, moves back in relation to the fuse, as the shell or bomb is shot forward, and thereby brings the striker needle and the detonator into contact with one another, causing detonation which drives the cutter into the tube, and said cutter formed with an opening which at one end is exposed to the flame of the detonation and at the other end is exposed at a side of the cutter in position to be exposed to the fuse material within the tube when the cutter has entered the tube, substantially as set forth.

5. A time fuse for an explosive shell or bomb, having a groove, a tube containing time fuse material located within such groove, a detonator, a cutter which is exposed to the force of the detonation, a striker needle, and a hammer which, owing to its inertia, moves back in relation to the fuse, as the shell or bomb is shot forward, and thereby brings the striker needle and the detonator into contact with one another, causing detonation which drives the cutter into the tube, and the operative portion of said cutter formed as a blade, substantially as set forth.

6. A time fuse for an explosive shell or bomb, having a groove, a tube containing time fuse material located within such groove, a detonator, a cutter which is exposed to the force of the detonation, a shearing pin which prevents such cutter from moving except under considerable force, a striker needle, and a hammer which, owing to its inertia, moves back in relation to the fuse, as the shell or bomb is shot forward, and thereby brings the striker needle and the detonator into contact with one another, causing detonation which drives the cutter

into the tube, the movement of the cutter shearing the shearing pin, substantially as set forth.

7. In a time fuse, the combination of a base, a head mounted thereon for rotative adjustment; a fuse carried by said base; a cutter carried by the head in line with the fuse; a fulminating device overlying said cutter; and a hammer arranged in line 10 with the fulminating device and adapted, upon impact, to explode said device and

thereby force the cutter into the fuse, rupturing the same and permitting ignition thereof.

In witness whereof I have hereunto signed 15 my name this 7th day of June, 1917, in the presence of two subscribing witnesses.

HERBERT AUSTIN.
